UNITED STATES PATENT OFFICE.

EDWARD B. WESTON, OF DAYTON, OHIO.

DISPLAY RACK.

1,427,248.

Specification of Letters Patent. Patented Aug. 29, 1922.

Application filed April 22, 1922. Serial No. 556,067.

To all whom it may concern:

Be it known that I, EDWARD B. WESTON, a citizen of the United States, and a resident of Dayton, in the county of Montgomery and State of Ohio, have invented certain new and useful Improvements in Display Racks, of which the following is a full, clear, and exact description, reference being had to the accompanying drawings, forming part of this specification.

The object of my invention is to provide a simple, cheap and effective rack for the display of goods in stores and the like, which is especially designed for the display of cartons and boxes of biscuits, crackers, cakes and other products and articles of merchandise which are usually packed in boxes or tins with transparent tops for the display of the goods, and in which it is desired to mount the box on the rack in tilted position while permitting the box to be opened from the front.

It is my object to supply a rack which can be shipped in knock-down condition adapted to be erected at a moment's notice and which shall be strong and rigid, adapted to be set up without liability of mistake by the most ignorant of storekeepers.

The invention consists of that certain novel construction and arrangement of parts to be hereinafter particularly pointed out and claimed.

In the drawings,

Figure 1 is a perspective view of the rack as a single unit.

Figure 2 is a similar view of one of the shelves.

Figure 3 is a detail showing the lock for the back shelf when shifted into forward position.

Figure 4 is a view of one of the cross braces.

The side standards comprise for each end of the rack, flat metallic bars 1, 1, integrally connected at the top by the arch 2 and braced together to form a rigid end frame by the cross braces 3, 3.

The shelves, all of which are of the same size and interchangeable, comprise an open metallic frame 4 with diagonal braces 5.

Two of these frames make up a shelf, one member is secured by bolts 6 and 7 in bolt holes through the end frames and shelf at such angle to the vertical as will give the desired display position for the box resting against it as a back, while the other shelf is

similarly secured by bolts 8 and 9 to the frame at an angle more nearly horizontal to receive the weight of the box and contents.

These shelf frames, when thus bolted to the end frames, form a rigid and substantial framework.

It has become common practice to provide containers of different depths for such goods, usually of uniform width and breadth, but one set of cartons of half the depth of the other set, and it is desirable to display the boxes with the fronts in alignment.

To provide for this, the back shelf is released at the bottom and swung inwardly into a position parallel with the line of tilt and in that position locked by the rear bolts, which have been loosened to permit the second adjustment. The smaller cartons are then rested against the longitudinal edge of the shelf so as to bring the fronts into the same alignment as for the full-sized boxes.

In order to secure the back shelf in this position, I provide lugs or bosses 10 in the uprights at the proper angle with the bolt hole and indent the ends of the frame at 14, 14, inside the bolt hole in the frame, so that the boss will engage the recess and the tightening of the bolt will hold the frame rigid to serve as a back for the smaller sized boxes.

In order that any desired number of these racks may be set up side by side, so that a sectional rack of as many units as required may be furnished, the cross braces 3, 3, for each standard are inset at 12, 12, so that the body of the braces will lie in the same plane with the standards. The bolts are long enough to hold a shelf on each side of the standard and a sectional rack of as many sections as desired is formed with a standard at each or either end and as many intermediate single standards as may be needed.

In order that the shelves can be held in position for the smaller cartons when units are secured together I form the lugs 10 on both sides of the standard, preferably by securing a rivet through the standard at the proper points and forming conical tips on the rivet where it projects at each side of the standard. I also form the indentations 14, 14, in all frames 4, which indentations are conical also.

The effect of the conical formation is to accurately center the parts when the shelves are elevated and the bolts 6 tightened.

All the parts are interchangeable so that there is no possibility of mistake in setting up. The racks can be taken apart and

shipped in very small space with the standards and shelves packed flat. The bolt holes are all punched with uniform spacing, and the recesses 14 are punched at each end of 5 the shelf frame near each bolt hole, so that all the parts will fit together accurately.

The rack as above described is inexpensive to manufacture and when set up forms a rigid and substantial structure adapted for 10 use for both sizes of cartons, while bringing all the cartons into alignment at the front.

The angular position of the shelves when bolted in position provides a much more rigid structure than would result if the 15 shelves were merely secured horizontally.

Having thus described my invention, what I claim as new and desire to secure by Letters Patent, is:—

1. In a display rack, metallic end standards with horizontal cross braces to brace and strengthen the standards, and a pair of similar rectangular metallic frames for each shelf section with similarly spaced bolt holes for each cross brace and similarly spaced 25 bolt holes for the end standards, located above the points of attachment of the cross braces, whereby the shelf members may be secured at a substantial angle to each other to hold the packages displayed in tilted position and all shelves may be interchanged.

2. In a display rack, metallic end standards with horizontal cross braces to brace and strengthen the standards, and a pair of

similar rectangular metallic frames for each shelf section with similarly spaced bolt holes 35 for each cross brace and similarly spaced bolt holes for the end standards, located above the points of attachment of the cross braces, whereby the shelf members may be secured at a substantial angle to each other 40 to hold the packages displayed in tilted position and all shelves may be interchanged, with each shelf section provided with a recess in the end near each bolt hole, and with lugs on the end standard to engage each its 45 respective recess to hold the rear shelf section in position to form a back support for smaller sized cartons.

3. In a display rack, metallic end standards with horizontal cross braces to brace 50 and strengthen the standards, and a pair of similar rectangular metallic frames for each shelf section with similarly spaced bolt holes for each cross brace and similarly spaced 55 bolt holes for the end standards, located above the points of attachment of the cross braces, each cross brace being bent at the ends so that the body of the brace will lie in the same plane with the end standards, whereby the shelf members may be secured at a substantial angle to each other and similar shelf members with similar standards 60 may be secured in line therewith to form a single display rack of a plurality of units.

EDWARD B. WESTON.
